RENÉ L. SALMON, OF PARIS, FRANCE.

LARGE-SIZED RESERVOIR FOR LIQUIDS.

Application filed November 23, 1926, Serial No. 150,300, and in France November 20, 1925.

This invention relates to the construction of large-sized reservoirs for liquids and chiefly of containers for storing petroleum and other hydrocarbons.

The reservoirs now used for storing petroleum are generally built of steel plates and have a cylindrical shape. A metallic reservoir containing 10,000 cubic meters of fuel and the shape of which is the usual 5 shape of a vertical cylinder having a diameter of 30 metres and a height of 14-30 metres necessitates its sides being built of plates the thickness of which varies from 5 to 25 mm., the mean thickness being thus 10 15 mm. This results in a great consumption of metal. Moreover the bottom of a cylindrical reservoir of this kind is a large circular plate having a diameter of 30 meters resting on the ground so that its several 20 parts cannot move easily relatively to one another when they expand under the action of variations of temperature. Further the lower surface of this bottom cannot be approached and therefore cannot be inspected 25 nor kept in good order.

The object of the invention described hereinafter is to provide an arrangement for reservoirs which overcomes these disadvantages. According to the present invention, 30 the reservoir comprises a number of supported ribs to which is secured a shell forming a series of small arches. The shell which receives directly the pressure of the liquid contained in the reservoir, transmits 35 it to the ribs which in their turn transmit it to their supports. The shell can easily expand by reason of its arched shape.

In a preferred form, a reservoir of this 40 type is placed inside a tubing to the walls of which are secured the supports of the ribs.

Such reservoirs can be constructed either of metal plates or of reinforced concrete.

Advantageous embodiments are provided 45 by disposing the ribs either along the generatrices of a horizontal cylinder or along the sections of such a cylinder perpendicular to the generatrices or along both directions so as to form a sort of net work, with 50 a metal shell the arches are preferably convex towards the outside so as to provide for operation under tension.

Where the reservoir is formed of rein-

forced concrete the arches are on the contrary made preferably convex towards the 55 inside with a view to provide for operation under compression.

The main advantages of such an arrangement are to allow free expansion in all directions of all the parts of the reservoir, to 60 economize the material to be used, to facilitate the inspection of the inner and outer walls and lastly in the case where the reservoir is placed in a tubing to prevent the liquid from being lost if the walls of the 65 reservoir should break open. This latter arrangement will be necessarily employed with buried reservoirs such as the hydrocarbon reservoirs established in view of war needs.

By way of example four forms of construction of reservoirs are described herein-after with reference to the accompanying drawings, in which:

Figs. 1, 2 and 3 relate to a reservoir of reinforced concrete disposed in tubing, the 75 ribs of the reservoir being disposed along the generatrices of a horizontal circular cylinder. These Figs. 1, 2, and 3 are respectively a longitudinal cross-section, a transverse cross-section and a plan view.

In a similar manner, Figs. 4, 5 and 6 relate to a reservoir of reinforced concrete also disposed in a tub, the ribs of which are disposed along the surface of a horizontal circular cylinder perpendicularly to the generatrices thereof.

Figs. 7, 8 and 9, refer to a metal reservoir disposed in a tub having ribs disposed along the surface of a horizontal cylinder perpendicularly to the periphery thereof.

Fig. 10 shows one of the supports of a rib.

Figs. 11, 12, 13 relate to a reservoir the shell of which comprises a number of spherical surfaces.

According to Figs. 1, 2 and 3, the reservoir formed of reinforced concrete comprises a number of horizontal ribs 1, 1', 2, 2', etc., disposed correspondingly two by two in a number of horizontal planes and connected at each extremity by arcuate members such as 1'', 2'', etc. Thus each horizontal plane considered contains a continuous rib comprising two parallel parts 1 1' connected at their extremities by the two part circular members 1''. Two adjacent ribs 1, 1', 1'' 105 and 2, 2', 2'' are connected together by a

continuous surface 10 the convexity of which is directed towards the inside so as to form an arch arranged for operation under compression under the action of the pressure of 5 the liquid in the reservoir.

The reservoir thus formed has the general shape of a cylinder with hollow longitudinal corrugations, the ends of which have a round shape and which is open at its upper 10 part. This reservoir is placed inside a tub provided in a base 11. In the several planes of the ribs 1, 1' etc. . . . are secured from place to place inside the tub supports 12 (Fig. 10) faced with a metal plate 13 bearing 15 against a metal plate 14 secured to the outside of the rib 1.

Each longitudinal rib is preferably secured at its middle as at 15. The reservoir is closed at its top part in a fluid tight manner by 20 means of a cover 16 formed of a shell of thin steel plate which can be easily deformed and secured at its edges to the shell connected to the ribs 1 and 1'. It is supported by light and easily deformable girders such as 17.

25 The circular parts such as 1'' placed at the ends of the ribs are provided with supports 18 resting on horizontal cradles 19 disposed on tiers of the tub. The expansion of such a reservoir is effected in the following manner. The longitudinal ribs such as 1, 1' secured at their middle at 15 expand freely in their horizontal plane towards their extremities.

30 The circular parts such as 1'' form semi-circular horizontally arranged arches and as their extremities cannot diverge laterally this arch when expanding develops into a slightly elliptical curve the major axis of which passes through the centre of the semicircular arch. It is easy to determine the shape and 35 size of these circular parts so as to prevent this elliptical deformation from straining these parts in any region beyond the safety point.

40 45 The shell of reinforced concrete provides for compression strains, whereby it can be given a very small thickness. The arches in each horizontal tier expand in the following manner:

50 1. Longitudinally together with the ribs formed at either end;
2. Transversely through a modification of the curvature of the arches. These are calculated in a manner such that the variations 55 of temperature do not make the concrete extend beyond the safety point where it would be drawn out and thereby cracked.

60 The inlet, outlet and blow-off piping is secured to the shell according to the usual methods.

65 The cover 16, by reason of its light weight can be easily deformed without ceasing to be fluid tight, so that it can follow without inconvenience the deformations of the aperture of the reservoir. This cover is provided with

a valve or with a device allowing air to enter and pass out of the reservoir.

Figures 4, 5 and 6 show a reservoir of reinforced concrete disposed in a tub and provided with ribs such as 20 formed by parts of 70 circles disposed along vertical transversal sections of the reservoirs and stopping at the two points 20', 20''. Each rib such as 20 bears against a number of supports 21 disposed perpendicularly to the corresponding 75 radius of the circle and secured to the tub in which the reservoir is located. The rib 20 is preferably secured at its middle to a support 22 placed at the lowest point. Between two adjacent ribs 20, 23 the shell comprises an arch 24 of reinforced concrete, the convexity of which is directed towards the inside. The reservoir thus comprises a cylinder the top of which is open and which shows hollow transverse corrugations. At each extremity, this cylinder is closed by an end formed for instance with a central circular part 25 and with a peripheral part 26 each of which is submitted to compression stresses like the arches. The top of the cylindrical 80 part is closed by a cover 27 the edges of which are connected in an airtight manner to those of the reservoir, the cover being yielding enough to follow all the deformations of the said reservoir.

85 The metal reservoir shown in Figs. 7, 8 and 9 is constructed in a manner similar to the reinforced concrete reservoir shown in Figs. 4, 5, 6: it comprises ribs such as 30 between which is disposed a shell forming arches such as 31. In order to set up stresses which may be resisted by the material used, i. e. metal plates, the arches 31 have their convexity directed towards the outside so as to resist tensional stresses. Under such 90 conditions, very thin plates can be used. For instance, if we consider the normal pressures, which as hereinbefore mentioned in cylindrical reservoirs necessitate plates having a mean thickness of 15 mm., it is sufficient with the method of construction described with reference to Figs. 7, 8 and 9, to use plates less than 5 mm. thick. At each extremity, this tubular reservoir is provided 95 with a spherical part 32 reinforced by a horizontal semi-circle 33 resting on a series 100 of supports 34 over which it can slide. The last transverse rib 35 bears along the whole of its periphery against a flange 36 disposed in the tub so as to prevent its moving when it expands longitudinally. When the ribs 30 expand each in its plane the last rib 35 is moved vertically whilst expanding in its own plane. The parts which bear on the supports 34 thus move obliquely, the supports 34 being given a corresponding inclination.

105 The reservoir shown on Figs. 11, 12, 13 comprises a system of parallel ribs similar to that shown in the reservoirs described 110

hereinabove, which system is completed by a second system of parallel ribs perpendicular thereto.

The spacing of the ribs in the second system is preferably equal to that of the ribs in the first system. The network formed by the two systems divides the shell into a number of squares in each of which the shell appears as a spherical surface which is either 10 concave or convex as explained hereinabove.

Such a spherical surface bounded by the sides of a square allows the metal to be submitted to stresses which under the same conditions are half those it would be submitted 15 to in a cylindrical arched surface of same curvature and spanning the same distance i. e. the distance between two opposite sides of the square. In a reservoir of the type shown, the strain of the metal is therefore 20 much smaller than in a reservoir of one of the two above described types.

The metal expands freely by reason of the deformation of the spherical surface which becomes ellipsoidal.

25 The joining surfaces between the adjacent spherical surfaces are curved in a direction opposite to the curvature of the said spherical surfaces and are provided by stamping and are bounded by the sides of the square 30 circumscribing each spherical surface.

The surfaces can be supported inside each square by either of the methods disclosed hereinbelow:

35 (a) The network of masonry acting as ribs supporting the metal sheets is continuous in which case the several sheets borne by the network of ribs are compressed when they are caused to expand. According to the 40 changes of temperature and the amount of liquid the extension due to the expansion may compensate the shortening due to the compression caused by the stress exerted on the metal or else the sheets may rise above the corners of the squares.

45 (b) The network of masonry ribs is pro-

vided only along a short length of the sides of the squares beginning at their intersections. On these elements of masonry is set a frame of strong stamped sheets showing 50 exactly the shape of the surfaces joining the spherical surfaces. The sheets constituting the walls of the reservoir are then set over the frame. In this case the expansion due to variations of temperature produces an extension of the sheets of the frame the curvature of which varies at the same time as the sheets themselves expand. 55

The secondary stresses developed in the sheets when the spherical surfaces are deformed and become ellipsoidal do not produce any dangerous stress in the metal; as on the other hand the outer frame of the first described reservoirs is rather costly, therefore it is of interest to use the last mentioned arrangement. 65

Figs. 11 to 18 show the two perpendicular equally spaced systems of ribs 37, 38. These ribs are borne by a network of concrete ribs 39, 40 resting on a base 41. Between the 70 ribs the sheets appear as stamped sheets having the shape of spherical surfaces 42.

The several arrangements disclosed hereinabove, especially the last provide reservoirs submitted to important pressures and constituted by comparatively thin sheets submitted to very small strains. They are adapted to be electrically welded whereby the necessity of riveting is removed and the fluid tightness of the reservoirs is increased. 75

What I claim is:

A reservoir for liquids comprising two perpendicular systems of ribs adapted to expand freely and a shell composed of elements having the shape of spherical surfaces and disposed inside each square formed by the intersection of the ribs. 85

In testimony whereof I have signed my name to this specification.
